UNITED STATES PATENT OFFICE.

HANS B. BEETZ, OF SAN FRANCISCO, CALIFORNIA.

FUR-PELT STRETCHER.

Application filed January 31, 1923. Serial No. 616,053.

To all whom it may concern:

Be it known that I, HANS B. BEETZ, a citizen of the United States, residing at the city and county of San Francisco and State of California, have invented new and useful Improvements in Fur-Pelt Stretchers, of which the following is a specification.

This invention relates to a fur pelt stretching apparatus.

10 It is the principal object of the present invention to provide a generally improved fur pelt stretching device which is simple in construction and operation and which may be employed to evenly and simultaneously stretch one or more pelts.

20 The invention contemplates the use of a stationary and a sliding frame, which carry co-operating pelt receiving racks, the sliding frame being operable to expand the racks and thereby to evenly stretch the pelts.

25 One form which the invention may assume is exemplified in the following description and illustrated by way of example in the accompanying drawings, in which:

Fig. 1 is a view in side elevation of the preferred embodiment of the invention.

30 Fig. 2 is an enlarged fragmentary view disclosing one of the stretching racks with a fur pelt positioned thereon.

Fig. 3 is a plan view of the device.

35 Fig. 4 is a section view taken on line 4—4 of Fig. 1.

Fig. 5 is a similar view taken on line 5—5 of Fig. 1.

40 Fig. 6 is a fragmentary view in perspective of the sliding frame.

Referring more particularly to the drawings, 10 indicates a fur pelt stretching device comprising an elongated frame 11. Secured to one face of the frame is a plurality of projecting arms 12 which are spaced equal distances apart.

45 The face of the frame upon which the arms are mounted, is longitudinally channeled as at 12^a. This channel or recess constitutes a guideway for a guide rail 14 of a sliding frame 15. This frame is fitted with an outer bar 16 which slides on a guide bar 17 mounted longitudinally of the main frame and secured along the lower ends of

50 the stationary arms 12. Arms 18 form a part of the sliding frame and are secured between the guide rail 14 and the outer bar 16. The arms 18 are identical in form to the arms 12 and are mounted in the same plane.

The arms 12 and 18 are arranged so that when the device is assembled, the arms will be arranged in pairs, each of which comprises an arm of each set. 60

The pairs of arms constitute fur pelt stretching racks and it is intended that the arms of each pair be separated after a pelt has been positioned thereon to stretch the pelt. For this purpose, the main frame is 65 apertured as at 19 to provide space for an adjusting screw 20. This screw has a grip portion 21 and a threaded end 22 which is threaded through an extension 23 on the main frame. The other end of the screw 70 is reduced in diameter and engages a thrust collar 24 secured on the end of the sliding frame. It is obvious that by turning the screw in one direction, the sliding frame will be forced along the main frame in a 75 direction which will separate the arms of the different racks.

In operation, the ends of the pelts to be stretched are stitched together to form tubes. These tubes are positioned over the 80 racks which are in contracted position. The screw 20 may then be manipulated to expand the racks to stretch the furs. When this has been accomplished, the screw may be manipulated to permit the racks to be 85 contracted so that the pelts may be removed.

As described, the arms of the racks are maintained parallel when separated, thus evenly stretching the pelts. This is a considerable improvement over prior devices 90 employed for this purpose. These prior structures comprised a pair of members hingedly connected at one end. The fur pelt was positioned over the rack thus formed and the free ends of the members 95 were then wedged apart to stretch the pelt. This type of rack did not evenly stretch the pelt.

While I have shown the preferred form of the invention, it is understood that various changes in its construction may be made without departing from the spirit of the invention as claimed. 100

Having thus described my invention, what I claim and desire to secure by Letters 105 Patent is:—

1. A fur pelt stretching device comprising a frame having a stationary arm secured thereon and positioned at right angles thereto, a second arm slidable on said frame and positioned parallel to the other arm, said 110 arms constituting a rack over which a pelt

may be positioned, and means for forcing said movable arm along the frame away from the stationary arm.

2. A fur pelt stretching device comprising a plurality of pairs of arms constituting racks over which fur pelts may be positioned, one arm of each rack being stationary, the other arm of each rack being movable in a direction at right angles to the stationary arms, and means for moving said movable arms away from the stationary ones simultaneously.

3. A fur pelt stretching device comprising an elongated main frame, arms secured to one face thereof and extending at right angles thereto, a sliding frame mounted for longitudinal movement on the frame, arms secured on the sliding frame co-operating with the arms on the main frame to form racks over which fur pelts may be positioned and means for moving the sliding frame along the main frame to expand the racks simultaneously.

4. A fur pelt stretching device comprising a main frame, a plurality of arms fixed at one end to said frame and extending substantially at right angles thereto, said frame having a guideway formed longitudinally thereof and in one side of the frame, a sliding frame having a guide rail slidably dis-

posed in said guideway whereby the sliding frame may be moved longitudinally of the main frame, arms fixed at one end to said sliding frame and projecting at right angles thereto parallel to said arms on the main frame, the arms on both frames being disposed in the same plane, and means for longitudinally moving the sliding frame with relation to the main frame.

5. A fur pelt stretching device comprising a main frame, a plurality of arms fixed at one end to said frame and extending substantially at right angles thereto, said frame having a guideway formed longitudinally thereof and in one side of the frame, a sliding frame having a guide rail slidably disposed in said guideway whereby the sliding frame may be moved longitudinally of the main frame, arms fixed at one end to said sliding frame and projecting at right angles thereto parallel to said arms on the main frame, the arms on both frames being disposed in the same plane, and means for longitudinally moving the sliding frame with relation to the main frame, said means comprising an adjusting screw one end of which is threaded through a portion of the main frame, the other end engaging the sliding frame.

HANS B. BEETZ.
